Primary Examiner—Terry A. Wallace*Attorney, Agent, or Firm*—Fitch, Even, Tabin & Flannery[57] **CLAIM**

The ornamental design for a bottle with embossed rope design, as shown and described.

DESCRIPTION

FIG. 1 is a front elevational view of a bottle showing our new design, the rear view being identical thereto;
FIG. 2 is a side elevational view thereof, the opposite side being identical thereto; and,
FIG. 3 is a top plan view thereof.

The bottom of the bottle forms no part of the claimed design.
